UNITED STATES PATENT OFFICE.

JEREMIAH CAMPBELL, OF PROVIDENCE, RHODE ISLAND.

COAL-DELIVERY WAGON.

No. 882,868.

Specification of Letters Patent. Patented March 24, 1908.

Application filed March 15, 1907. Serial No. 362,538.

To all whom it may concern:

Be it known that I, JEREMIAH CAMPBELL, of Providence, in the county of Providence and State of Rhode Island, a citizen of the United States, have invented a new and useful Improvement in Coal-Delivery Wagons, of which the following is a full, clear, and exact description, reference being had to the accompanying drawings, forming a part of this specification, in explaining its nature.

My invention consists primarily in a coal delivery wagon from which coal is delivered at the side of the wagon so that it is unnecessary to back up the wagon in order to deliver the coal.

My invention consists, also, in a delivery wagon having a plurality of compartments from each one of which coal may be delivered so that the wagon may carry different kinds of coal at the same time.

My invention consists also in various details of construction all of which can best be seen and understood by reference to the drawings in which--

Figure 1 is a side elevation of a wagon embodying my invention. Fig. 2 is a cross section on the line 2--2 of Fig. 1. Fig. 3 is a horizontal section on the line 3--3 of Fig. 1. Figs. 4 and 5 are enlarged details of construction to which especial reference will be made. Fig. 6 shows mainly in side elevation a portion of a wagon showing a further embodiment of my invention to which special reference will hereinafter be made. Fig. 7 shows a cross section on the line 7--7 of Fig. 6.

In the drawings:—A represents a wagon the running gear of which supports a body B which by means of a partition C and folding doors C¹, C², hinged to the partition by the hinges c, is divided into separate compartments or bins D, D¹. These compartments have floors or bottoms d and d¹, respectively, inclined towards the outlets of the compartments, and it is these outlets from the compartments which the folding doors C¹, C² are adapted to close. These doors when closed occupy an inclined position so that when the doors are opened they will swing but a short distance below the lower ends of the inclined bottoms to the separate compartments and not to interfere with the chute into which the compartments empty. On this account the doors are hinged to the partition C at a point above the lower ends of the inclined bottoms to the respective compartments. Inasmuch as the doors are hinged at a point not only

above but beyond the lower ends of the inclined bottoms to the respective compartments they hang normally in a vertical, open position with respect to the outlets to the compartments. The folding doors are shown in their closed position and each door is so held by means of a series of fingers e, each of which is attached to a rod E mounted in eyes e¹, one on each side of the body of the wagon. The rod E passes out through one side of the body of the wagon and connects outside thereof with a handle e² which, when the parts are in the position shown in Fig. 1, engages with a spring latch e³ on the outside of the wagon body. This latch is preferably a hook between which and the end of the handle there will be play enough to allow the end of the handle to engage it and be disengaged therefrom, (see Fig. 4.) This construction is the same with both doors C¹, C², both handles e² preferably being on the same side of the wagon.

Both compartments D and D¹ empty into a common delivery chute F, the inclined bottom f of which leads to the side of the wagon. The lower end of the chute F is closed by a swinging door G which is hung from the bottom of the wagon at the top of the chute by hinges g. The door is provided with a locking means consisting of a rod g¹ hung in eyes g² dependent from the lower end of the chute. The rod g¹ carries fingers g³ adapted as shown in Fig. 2 to hold the swinging door G in place to close the chute. An arm g⁴ mounted on one end of the rod g¹ projects upward and is connected by a hook g⁵ with an eye g⁶ on the under part of the body of the wagon. This hook g⁵ can be readily unhooked so that the arm g⁴ may be swung outward and the door G released to open allowing the load from the chute to pass out.

In addition the door G has the usual slide customary in the tail-board of coal and other wagons. This slide is shown at H confined in ways formed by the strips h, the slide being provided with a handle h¹ so that it may be moved up and down. This slide may be used when the coal is to be unloaded by basket.

In Figs. 6 and 7 I have shown a wagon having a plurality of coal carrying compartments and chutes leading to different or opposite sides of the wagon.

The coal carrying compartments are D and D¹ as before described separated by the partition C and with the outlets of the com-

partments closed by the swinging doors C¹, C², respectively.

Both the compartments D and D¹ empty into what may be termed a combined hopper and chute F¹; a hopper in the sense that it receives the coal from the several compartments preparatory to its delivery from the wagon, and a chute that it properly directs and assists in the delivery of the coal into the chutes F² and F³ extending from the hopper to the opposite sides of the wagon. This hopper F¹ is preferably made V-shaped with inclined sides f¹ and f². These sides comprise in part folding doors f³, f⁴ which are hinged at the point f⁵ and open outwardly into the chutes F², F³. These doors are shown closed, which is their normal position, and they are held so closed, but so as to be released to open in the following manner:—

10 Fastened to the upper end of each door, or rather to a lug f⁶ projecting therefrom, is a chain f⁷. This chain is adapted to be wound upon or unwound from a shaft f⁸ by which means the door is closed and held closed, or released to open (see Fig. 7). Each shaft f⁸ extends through the side wall of the chute F² or F³ with which it connects, and on the outer end of the shaft, outside the chute, is a gear f⁹. Meshing with this gear is a gear f¹⁰ arranged on the end of a shaft f¹¹ which extends toward the side of the wagon and is journaled in a proper fixture of support f¹² secured to the body of the wagon. The ends of the shaft f¹¹ are accessible from the sides 35 of the wagon and are adapted to receive instruments by which the shaft may be turned so operating the folding doors as aforesaid. As said before, the chutes F², F³ lead, respectively, to opposite sides of the wagon so that 40 as one door f³ or the other door, f⁴, is opened the coal will be directed into one chute or the other and thereby be delivered from the corresponding side of the wagon. In this connection it is to be noted that the sides of 45 the hopper F¹ preferably have the same inclination as the bottom f¹³ and f¹⁴ of the chutes F², F³ extending from the hopper, so that when one door of the hopper is opened

there will be practically one continuous chute leading from the coal containing compartments, which chute is in part provided by the hopper and in part by the chute proper, so insuring a quick and direct delivery of the coal. The lower end of each of the chutes is closed by a door G in the manner as before described. 50 55

In using the wagon, either bin may be discharged separately or both bins may be discharged together and a movable chute may be set up into which the coal will fall as it is delivered from the wagon and moved off to the place of final discharge, or the coal may be discharged by lifting the door G, as above described. 60

The advantage of this wagon will be apparent to those skilled in the art. The wagon is driven to the curb for unloading like any express or grocer's wagon. It may bring two kinds of fuel to the same house or it may bring a load of fuel to one house and 70 after delivering it carry the contents of its other bin to another place of delivery, or both bins may be filled with the same coal for the same location. 75

Having thus fully described my invention, I claim and desire to secure by Letters Patent of the United States:— 75

1. A wagon having a plurality of coal-carrying compartments, a hopper common to said compartments, releasable means closing each of said compartments from said hopper, a chute leading from said hopper, and releasable means closing said hopper from said chute. 80

2. A wagon having a plurality of coal-carrying compartments, a hopper common to said compartments into which the coal empties therefrom, releasable means closing each of said compartments from said hopper, a plurality of delivery chutes leading from 90 said hopper, and releasable means closing said hopper from each of said chutes. 85

JEREMIAH CAMPBELL.
